UNITED STATES PATENT OFFICE.

EZRA G. CLYMANS AND MELVIN A. FLAUTT, OF WAYNESBORO, PENNSYLVANIA, ASSIGNORS
TO THE GEISER MANUFACTURING COMPANY, OF WAYNESBORO, PENNSYLVANIA.

CHAFF-SEPARATOR.

No. 901,883.

Specification of Letters Patent.

Patented Oct. 20, 1908.

Application filed January 30, 1908. Serial No. 413,422.

To all whom it may concern:

Be it known that we, EZRA G. CLYMANS and MELVIN A. FLAUTT, residing at Waynesboro, in the county of Franklin and State of Pennsylvania, have invented certain new and useful Improvements in Chaff-Separators; and we do hereby declare the following to be a full, clear, and exact description of the invention, such as will enable others skilled 10 in the art to which it appertains to make and use the same.

This invention relates to the chaff-catchers or chaff-bottoms used in threshing-machines or grain-separators; and it consists in the 15 novel construction and combination of the parts hereinafter fully described and claimed whereby the chaff may be collected separate from the straw or discharged with it, at will.

In the drawings, Figure 1 is a longitudinal 20 section through the chaff separating mechanism, showing it out of action. Fig. 2 is a longitudinal section through a portion of the chaff-catcher, drawn to a larger scale and showing the trap-door raised and the bottom 25 section of the conveyer spout closed. Fig. 3 is a plan view of the same. Fig. 4 is a longitudinal section through the conveyer and discharge fan.

A is the rear end portion of the casing of 30 a threshing-machine or grain-separator of any approved construction.

B is a portion of the grain-pan or grain-bottom on which the grain falls from the straw-racks, and C is the chaff-catcher or chaff-bottom arranged under the grain-pan 35. B. The chaff is normally blown out of the rear end of the machine onto the straw-stack by a blast of air which is driven between the parts B and C in the direction of 40 the arrows, and a portion of the chaff falls on the chaff-catcher and is discharged by it. The chaff-catcher is supported in the casing and is operated in any approved manner.

In order to collect the chaff separate from 45 the straw, the chaff-catcher C is provided with a trap-door C' having a hinge c at its rear edge and opening upwardly.

D is a forked bracket secured to one side of the chaff-catcher, and d is a second forked 50 bracket also secured to one side of the chaff-catcher to the rear of the bracket D and adjacent to the hinge of the door.

E is a bracket secured to the trap-door, and provided with a longitudinal slot e. 55 F is a catch which is slidable in the slot e,

and f is a thumb-nut for securing the said catch in the slot. When the trap-door closes the opening c' the catch F engages with the bracket D, and the chaff is blown out at the rear end of the machine onto the straw-stack. When the trap-door is opened, as shown in Fig. 2, the catch is slid into engagement with the bracket d, and the blast of air is obstructed so that most of the chaff falls through the opening c' in the chaff-catcher. 60 65

G is the chaff-spout under the trap-door. This spout is provided with a removable bottom section g, which may be taken off altogether, but which is preferably connected to the main portion of the spout by hinges h 70 and a catch h'.

H is a spiral conveyer of any approved construction provided with a driving shaft i and arranged in the conveyer spout.

I is a fan casing at one end of the conveyer 75 spout, and J is a discharge fan of any approved construction secured on the shaft i and arranged in the casing I. The shaft i is journaled in bearings i' of any approved construction, which are supported from the 80 casing A.

K is a driving pulley which is journaled on one end portion of the shaft i. A collar k is secured to the shaft i on one side of the pulley, and the pulley is provided with a 85 clutch-member m on its hub on the other side of it from the collar k. A removable and reversible clutch-member n is secured to the shaft i by a set-screw i' or any other approved means. 90

When the trap-door is closed the position of the clutch-member n is reversed on the shaft, so that the shaft is not revolved by the driving pulley.

The object in providing the chaff spout 95 with a hinged bottom section is to enable it to be discharged of the accumulation of dirt and fine chaff which finds its way into it when the trap-door is closed and which becomes packed into a dense mass after the 100 machine has been at work for a considerable time with the trap-door closed.

The fan I discharges the chaff through its delivery pipe p into any convenient receptacle. 10.

What we claim is:

1. The combination, with the rear end portion of a grain-separator, and a grain-pan arranged therein; of a chaff-catcher arranged below the said grain-pan and pro- 110

vided with an opening, and a door pivotally connected to the rear side of the said opening and operating when raised to obstruct the rearward current of blast and chaff between the said grain-pan and chaff-catcher, so that the chaff falls through the said opening.

2. The combination, with the rear end portion of a grain-separator, and a grain-pan arranged therein; of a chaff-catcher arranged below the said grain-pan and provided with an opening, a door pivotally connected to the rear side of the said opening and operating when raised to obstruct the current of blast and chaff between the said grain-pan and chaff-catcher, and catch mechanism for securing the said door in different positions.

3. The combination, with the rear end portion of a grain separator, of a chaff-catcher supported therein and provided with an opening, a door normally closing the

said opening, and means for supporting the said door in a raised position at the rear side of the said opening to obstruct the rearward current of blast and chaff, so that the chaff falls through the said opening. 25

4. The combination, with a chaff-catcher provided with an opening, of a conveyer spout secured under the said opening, a fan 30 casing secured at one end of the said spout, a driving shaft arranged in the said spout and casing, a spiral conveyer secured on the said shaft and arranged in the said spout, a delivery fan secured on the said shaft and 35 arranged in the said casing, and trap-door for closing the said opening.

In testimony whereof we affix our signatures, in presence of two witnesses.

EZRA G. CLYMAN. 35
MELVIN A. FLAUTT.
